CLAIM

The ornamental design of a motor housing for a linear actuator, as shown and described.

DESCRIPTION

FIG. 1 is a perspective bottom view of a motor housing for a linear actuator showing my new and ornamental design,
FIG. 2 is a perspective top view thereof,
FIG. 3 is a perspective top view similar to FIG. 2 with the cover removed,
FIG. 4 is a top plan view thereof with the cover removed,
FIG. 5 is a bottom plan view thereof,
FIG. 6 is a left side view thereof,
FIG. 7 is a right side view thereof,
FIG. 8 is a rear end view thereof; and,
FIG. 9 is a front end view thereof.
